TARGET PRACTICING AND AMUSEMENT DEVICE

Lyndon A. Durant, Chicago, Ill., assignor to General Patent Corporation, Chicago, Ill., a corporation of Illinois

Application November 16, 1954, Serial No. 469,159

4 Claims. (Cl. 273—101.2)

This invention relates to certain new and useful improvements in a target practicing and amusement device and more particularly to a novel and improved arrangement for mounting a simulated rifle or gun upon a gun cabinet forwardly of the targets whereby the operator or user of the rifle may manipulate the same with ease and with accuracy.

Another object of the invention is the provision of a novel arrangement for applying friction to a supporting element of the rifle whereby to regulate the movement thereof over the target range.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a target apparatus showing my invention associated therewith;

Fig. 2 is a fragmentary sectional detail view taken substantially on line 2—2 of Fig. 3;

Fig. 3 is a fragmentary sectional detail view taken substantially on line 3—3 of Fig. 4;

Fig. 4 is a fragmentary sectional detail view taken substantially on line 4—4 of Fig. 3;

Fig. 5 is a fragmentary sectional detail view taken substantially on line 5—5 of Fig. 3;

Fig. 6 is a fragmentary sectional detail view taken substantially on line 6—6 of Fig. 4;

Fig. 7 is a fragmentary sectional detail view taken substantially on line 7—7 of Fig. 4.

The several objects of this invention are accomplished by the preferred form of construction shown in the accompanying drawings and which construction comprises a cabinet 10 having an upper cabinet portion 11 within which is arranged a target range or field 12. Forwardly of the cabinet 10 is a gun mounting base 13. This base 13 has a mounting plate 14 provided with a central opening 15 circular in plan view and which opening has arranged therein a spherical enlargement 16 of a sleeve 17. The enlargement 16 is connected for oscillatory movement by means of trunnions 18, the ends of which are journalled in suitable bearings 19 provided by the plate 14.

Mounted for rotation about a vertical axis within the sleeve 17 is a supporting shaft 20, the upper end of which is fixedly secured in a socket 21 provided by a bearing 22 extending downwardly from and formed as a part of the stock 23 of a simulated rifle 24. The bearing 22 rests upon the sleeve 17 and therefore positions the rifle 24 with respect to the sleeve 17. The shaft 20 extends downwardly from the sleeve 17 as at 25, through a yoke or strap 26. This strap 26 comprises a bar 27 secured by means of thumb nut bearing bolts 28 to a wall 29 of the gun mounting cabinet 13.

Disposed in parallel relation with respect to the bar 27 is a second bar 30. This bar 30 is mounted upon

2

the threaded end portions 31 (Fig. 6) of stud shafts 32 fixedly carried as at 33 by the bar 27. The length of the stud shaft 32 is of a dimension less than the diameter of the shaft 20 so that wing nuts 34 threaded upon the threaded end portions 31 will bear the medial portion of the bar 30 against the lower end portion 25 of the shaft 29, thereby to increase or decrease the frictional engagement between the yoke 26 and the shaft end portion 25 to regulate the freedom of movement of the rifle 24 through a vertical or a tilting horizontal plane. By this arrangement, whenever the user releases his grip upon the rifle, the rifle will remain in the position at the time of release and yet will have sufficient freedom of movement to enable the user to accurately aim the rifle or adjust its position.

As shown in Figs. 1 and 3, a chain 35 has one end 36 secured to the barrel of the rifle and its opposite end 37 to the top wall 38 of the cabinet 13, whereby to limit the vertical and horizontal movement of the rifle.

20 Pivots secured to the end of the shaft portion 25 by means of a pintle 39, is a scanning arm 40 yieldably retained with its contacts 41 upon a contact plate 42 by means of a spring 43 which embraces the shaft end portion 25 with its opposite end portion secured to a post 25 44. These contacts 41 are yieldably held by springs 45 in contact with a contact bearing plate 46 for engagement with the contacts 47 carried by such plate. These contacts 41 and 47 are arranged in an electrical circuit such as shown in my copending application filed on even date 30 hereof, Serial No. 469,158. Such circuit constitutes no part of this present invention.

A bar 48 extends transversely of the scanning arm 40 and is supported in such position by lugs 49 struck from a mounting plate 50. This mounting plate 50 is supported 35 by the arms 51 from the side walls 52 of the gun cabinet 13. The inner edge portion 53 of the plate 50 is turned downwardly to provide a flange 54. The plate 50 provides an opening 55 through which projects a depending lug 56 provided by a plate 57 mounted for adjustment 40 relative to the plate 50 and having adjustably connected thereto by means of wing nut carrying bolts 58 projecting through slots 59, the plate 46. The plate 50 is provided with guide slots 60 into which project guide pins 61 carried by the plate 57. The depending lug 56 and the flange 54 are threadedly connected together by a 45 thread bearing screw 62 having a knurled finger nut 63. By rotating the screw 62, the plates 57 and 50 may be adjusted relative to each other. By this arrangement and the arrangement of the slot and bolt connections, 58 and 59, the contact bearing plate 46 may be adjusted in a 50 proper position for engagement with the selector contacts 41.

An arrangement is provided to effect a noise simulating the report of a gun being fired. This arrangement 55 comprises a yoke 64 embracing the shaft end portion 25 and connected by bolt 65 to the plunger 66 of an electromagnetic solenoid coil 67 in turn supported as at 68 from and beneath the plate 14. This coil is arranged in a circuit with the rifle so that each time the trigger of the simulated rifle 24 is pulled, the coil will 60 become energized and effect a striking of the yoke 64 against the shaft end 25, thereby to effect the simulation of a report of a gun.

It will be apparent that my invention comprises relatively few parts, thereby enabling assembly of the same at the most economical cost. The construction hereinbefore described affords adjusting the movement of the simulated rifle to achieve the most realistic effect in the handling and aiming of the simulated rifle. Such construction prevents the rifle from banging or otherwise 70 striking against the surface of the cabinet on which it is mounted, thereby preventing damage.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a target practicing apparatus, the combination with a simulated rifle, of a mounting for the rifle comprising a structure carrying the rifle for movement through a horizontal plane and a vertical plane, means operable on said structure to vary the freedom of movement of said rifle through said planes, said last-named means including a shaft end portion included as a part of said rifle mounting structure, and a yoke embracing said end shaft portion and comprising a fixed member and a member adjustable relative to the fixed member to frictionally engage said shaft end portion. 20

2. In a target practicing apparatus, the combination with a simulated rifle, of a mounting for the rifle comprising a structure carrying the rifle for movement through a horizontal plane and a vertical plane, means operable on said structure to vary the freedom of movement of said rifle through said planes, said last-named means including a shaft end portion included as a part of said rifle mounting structure, a yoke embracing said end shaft portion and comprising a fixed member and a member adjustable relative to the fixed member to frictionally engage said shaft end portion, and means to limit the movement of said rifle through said planes. 25

3. In a target practicing apparatus, a mounting plate having a circular collar formed on one surface thereof, a sleeve having a spherical enlargement positioned in said collar, a pin pivotally connecting said enlargement to

5 said collar for mounting said sleeve on said plate for pivotal movement through a vertical plane, a rifle having a socket portion, a supporting shaft for said rifle having one end portion fixedly secured in said socket portion and projecting through and below said plate, said socket portion cooperating with said supporting shaft to position said rifle upon said sleeve for pivotal movement through a horizontal plane, and means for resisting the movement of said supporting shaft and said sleeve when said rifle is moved through said vertical or horizontal plane. 10

4. In a target practicing apparatus, a mounting plate having a circular collar formed on one surface thereof, a sleeve having a spherical enlargement positioned in said collar, a pin pivotally connecting said enlargement to said collar for mounting said sleeve on said plate for pivotal movement through a vertical plane, a rifle having a socket portion, a supporting shaft for said rifle having one end portion fixedly secured in said socket portion and projecting through and below said plate, said socket portion cooperating with said supporting shaft to position said rifle upon said sleeve for pivotal movement through a horizontal plane, means for resisting the movement of said supporting shaft and said sleeve when said rifle is moved through said vertical or horizontal plane, said last-named means comprising a yoke embracing said supporting shaft and including a fixed member and a member adjustable relative to said fixed member to frictionally engage said fixed member and said adjustable member with respect to said supporting shaft. 20
